UNITED STATES PATENT OFFICE.

JOHN D. HOOD, OF PHILADELPHIA, PENNSYLVANIA.

ENGINE VALVE GEAR.

1,414,739.

Specification of Letters Patent. Patented May 2, 1922.

Application filed October 6, 1919. Serial No. 328,693.

To all whom it may concern:

Be it known that I, JOHN D. Hood, a citizen of the United States, residing at Philadelphia, in the county of Philadelphia and State of Pennsylvania, have invented 5 certain new and useful Improvements in Engine Valve Gears; and I do declare the following to be a full, clear, and exact description of the invention, such as will enable 10 others skilled in the art to which it appertains to make and use the same.

My invention relates to improvements in engine valve gears and the present embodiment thereof is shown in connection with a 15 locomotive, although it is intended that it shall be used to equal advantage on other forms of steam engines.

The principal object of my invention is to provide a valve gear simplifying, cheapening and generally improving prior devices, 20 and with this in view, the invention resides in the novel construction and arrangement of parts hereinafter described and claimed, the descriptive matter being supplemented 25 by the accompanying drawings.

Figure 1 is a side elevation of a valve gear constructed in accordance with my invention.

Fig. 2 is a top plan view of the parts 30 shown in Fig. 1.

Fig. 3 is a plan view of the horizontal lever which is actuated from the pitman, showing the suspending link of this lever and the vertical operating lever in horizontal section.

Figures 4 and 5 are side elevations with parts in section showing the mechanism set for forward driving and reversing, respectively.

In the drawings above briefly described, 40 the numerals 1 and 2 designate respectively the cylinder and steam chest of a locomotive, 3 has reference to the crosshead, 4 refers to the piston rod, 5 indicates the pitman and 6 45 designates the stem which operates the usual slide valve (not shown) within the steam chest 2. All of these parts are of the usual or any suitable construction and form no part of my invention except in connection 50 with the parts hereinafter pointed out.

A bracket or other suitable support 7 is provided for a vertical suspending link 8, the upper end of said link being by preference forked at 9 to straddle said bracket, to 55 which it is suitably pivoted at 10. The lower end of link 8 is forked at 9^a and is

fulcrumed to a horizontal lever 11 between the ends of the latter, the rear end of said horizontal lever being pivoted at 12 to the pitman 5 while the front end of said lever 60 is pivotally connected at 13 to the lower forked end 14^a of the vertical operating lever 14.

The upper end of lever 14 is forked at 14^b and fulcrumed at 16 to a pair of substantially horizontal links 17 which are pivoted at 18 to crank arms 19 on the usual transverse rock shaft 20.

This rock shaft is connected by suitable means such as the crank arm 21 and rod 22 70 with the usual reverse lever (not shown). At 23, the rear end of the valve operating radius rod 24 is pivoted to the lever 14 between the fork arms and a short distance below the fulcrum 16, the front end of said 75 link 24 being pivoted to the valve stem 6.

In operation, the pitman 5 swings the lever 11 upon its fulcrum 15 and at the same time moves said lever forwardly and rearwardly, during which movement the suspending link 80 8 swings in the necessary manner. The above described movement of lever 11 shifts the valve operating lever 14 upwardly and downwardly and at the same time rocks said lever upon its fulcrum 16, and the combination of movement set forth reciprocates the valve stem 6 in the proper manner for actuating the usual slide valve. The movement of this valve may be controlled in the usual way by adjusting the rod 22 and reversing may also be effected by shifting said 85 rod in the proper manner. (See Fig. 5.)

The principal improvements which I have made over the prior art, are in mounting the horizontal lever 11 upon a swinging link 95 and in pivoting the rear end of said lever directly to the pitman rather than to a slide on said pitman. These changes greatly simplify and cheapen previous structures without decreasing their advantages in any manner whatsoever.

Since probably the best results are obtained from the details disclosed, they may well be followed, but within the scope of the invention as claimed, minor changes may be 105 made and obviously the valve gear may be employed on numerous forms of steam engines, although the present disclosure is directed to a locomotive valve gear.

I claim:

In a steam engine valve gear, the combination with a slide valve rod, a piston rod be-

low said valve rod, a pitman pivoted to said piston rod, and a relatively fixed frame structure; of a vertical link pivoted at its upper end to said frame structure in a plane 5 above said valve rod, the lower end of said link being in substantially the same plane as said pitman and spaced outwardly from the latter, a substantially horizontal lever fulcrumed between its ends to the lower end of 10 said link, the rear end of said lever being offset inwardly and pivoted directly to said pitman while the front end of said lever is offset outwardly, a substantially vertical lever parallel with and spaced forwardly

from said vertical link, a pivot connecting 15 the lower end of said vertical lever with the front end of said horizontal lever, a substantially horizontal link pivoted at its rear end to the upper end of said vertical lever and forming a fulcrum therefor, means 20 pivotally mounting the front end of said horizontal link on said frame structure, and a connecting rod pivoted to said vertical lever and to said valve rod.

In testimony whereof I have hereunto set 25 my hand.

JOHN D. HOOD.
